GOLF PUTTER HEAD

Arthur B. Carper, Denver, Colo.

Application December 22, 1955, Serial No. 39,432

Term of patent 14 years

(Cl. D34—5)

Fig. 1 is a top view of a golf putter head showing my new design;

Fig. 2 is a far side, elevational view thereof;

Fig. 3 is a bottom view thereof;

Fig. 4 is a near side, elevational view thereof; and

Fig. 5 is a front face view thereof.

I claim:

The ornamental design for a golf putter head, as shown.
